UNITED STATES PATENT OFFICE.

JAMES ARTHUR HEWES, OF MELROSE, MASSACHUSETTS.

DESIGN FOR A SUSPENDER-END.

SPECIFICATION forming part of Design No. 29,203, dated August 9, 1898.

Application filed December 10, 1896. Serial No. 615,215. Term of patent 3½ years.

To all whom it may concern:

Be it known that I, JAMES ARTHUR HEWES, a citizen of the United States, residing at Melrose, in the county of Middlesex and State 5 of Massachusetts, have invented and produced a new and original Design for Suspender-Ends, of which the following is a specification, reference being had to the accompanying drawings, forming part thereof.

Figure 1 is a face view of a suspender-end containing my design. Figs. 2 and 3 are sections on lines 2 2 and 3 3, respectively, of Fig. 1.

The leading feature of my design consists 15 in a suspender-end comprising an oval depressed name-space and subjacent trifoliate bearing for duplex buttonhole-cords.

A is an oval depressed name-space.

B B' B² constitute the subjacent trifoliate 20 bearing, the bottom of the middle bearing member b' projecting below the outer bearing members B and B².

Buttonhole-cord D comprises two body portions d and d', portion d rendering through 25 members B and B², which constitute the upper and outer members of the trifoliate bearing, and portion d' rendering through the

member B', which constitutes the middle and lower member of the trifoliate bearing. The inner edges of the outer leaves b, which are 30 looped to form the outer and upper bearings B and B', form the upper and side walls a of the oval depressed name-space A and partially inclose the oval depressed name-space A, the lower wall portion a' being formed by 35 the edge of the middle leaf b', which is looped to form the middle lower bearing B'. The collocated walled name-space and subjacent trifoliate button-cord bearing form the distinguishing part of my new design, which 40 produces a new and ornamental effect in suspender-ends.

What I claim is—

The design for a suspender-end substantially as shown and described. 45

In testimony whereof I have signed my name to this specification, in the presence of two subscribing witnesses, on this 28th day of November, A. D. 1896.

JAMES ARTHUR HEWES.
